COMBINATION CLOSURE CAP AND SIPPER

Earl S. Tupper, Smithfield, R.I., assignor to Tupper Corporation, North Smithfield, R.I., a corporation of Delaware

Application December 18, 1956, Serial No. 44,240

Term of patent 14 years

(Cl. D58—26)

I claim:

The ornamental design for a combination closure cap and sippy, substantially as shown.
